BAILER WITH AUTOMATIC DISCHARGE RELIEF VALVE

William J. Flury, Long Beach, Calif., assignor of
one-third to Frank Halfen and one-third to
Louis P. Brandel, both of Long Beach, Calif.

Application April 27, 1936, Serial No. 76,652

12 Claims. (Cl. 166—19)

This invention has to do in a general way with oil well operations and is more particularly related to bailers of the so-called "suction" or "differential pressure" type. As is well known to those familiar with the art, differential pressure bailers of this general character are extensively used for the purpose of removing sand and other debris from the bottom of oil wells and embody a sand chamber and an air chamber separated by suitable valve means and adapted to be filled with pressure fluid from the well when the bailer engages the bottom thereof. Both of the chambers are filled with pressure fluid from the bottom of the well, the sand chamber being provided with a check valve to retain the fluid within the bailer and a discharge valve to permit its being unloaded at the surface of the ground.

It is a primary object of this invention to provide a telescoping bailer of the class described which is of simple form and construction and which incorporates novel valve means for establishing communication between the air chamber and the sand chamber when the unit is telescoped at the bottom of a well, such valve being designed to automatically open when the discharge valve is opened whereby a compressed gas or pressure fluid in the air chamber is effective to force the fluid from the sand chamber irrespective of any telescoping movement between the bailer sections, thereby facilitating the unloading of the bailer. More specifically, my invention contemplates the provision of a double purpose valve which is automatically effective to eliminate the difficulties ordinarily encountered in dumping or unloading the bailer. This is accomplished by providing a downwardly opening valve within the bailer unit between the air chamber and the sand chamber, such valve being arranged so that it is normally closed whenever the unit is suspended (either empty or filled with pressure fluid) and at the same time is adapted to be automatically opened, with the bailer sections extended, by the pressure in the air chamber when it becomes greater than the pressure in the sand chamber such as is occasioned when the discharge valve in the sand chamber is opened.

In this way I eliminate the necessity of employing latch means in conjunction with the intermediate valve, such as have heretofore been used to hold such valve in open position when the unit is being withdrawn from the well, and I provide a unit which can be unloaded independently of any movement between the two members of a bailer of the telescoping type. In other words, the unit contemplated by this invention

may be unloaded while it is suspended from the line or cable or it may even be unloaded when it is in a substantially horizontal position.

It is a still further object of this invention to provide a valve of the class described which will be immediately opened without any delayed movement whenever the telescoping sections of the bailer are collapsed.

The details in the construction of certain preferred forms of my invention, together with other objects attending its production will be best understood from the following description of the accompanying drawing which are chosen for illustrative purposes only and in which:

Fig. 1 is a side elevation with parts broken away showing a preferred form of bailer contemplated by this invention;

Fig. 2 is an enlarged sectional elevation taken along the line 2—2 of Fig. 1 showing the telescoping joint between the two sections of the bailer shown in Fig. 1 and further illustrating details in the construction of a preferred form of valve mechanism contemplated by the invention.

Fig. 3 is a fragmentary sectional elevation along the line 3—3 of Fig. 2 showing the unit as having been collapsed to open the valve for loading the bailer;

Fig. 4 is a plan section on the line 4—4 of Fig. 3.

More particularly describing the invention as herein illustrated, reference numeral 11 indicates a bailer which is formed of two telescoping members 12 and 13. The upper or inner member 12 which may be termed the air chamber is provided with a cover cap 15 of conventional type, such cap being provided with a ring or link member 16 to which suspending means such as a cable 17 may be attached.

The bottom of the lower or outer member 13 is shown as being provided with a conventional inlet and discharge shoe indicated by numeral 18 which is shown as having a "bull nose" 19 and is equipped with an inwardly opening check valve of the flapper type indicated at 20. The discharge valve on this shoe may be of any conventional type and is shown as comprising a sleeve 21 having ports 22 therein. The ports 22 are adapted for alignment with ports 23 in the wall of the shoe when the sleeve 22 is rotated.

The inner member 12 is shown as having a section 52 of reduced diameter which extends downwardly through a bushing 53 and a packing gland 54 into the upper end of the outer member 13. The bushing 53 and the packing gland 54 are shown as being contained in a fitting 55 which is threaded in the top of the member 13 as in-

dicated at 56 and which provides a shoulder 57 within the member 51 at its upper end. This shoulder 57 is preferably formed with a valve face and is adapted to be engaged by what I may term a valve or seal member 58 threaded on the lower end of the portion 52.

Mounted on the lower end of the portion 52 below the valve member 58 is what I may term a cage member 59 which is ported as indicated at 60 and has downwardly extending legs 61 and 61' terminating in a cross member 62. This cross member 62 is provided with a central passage indicated at 63 through which a reduced end portion 64 on a valve stem 65 slidably extends.

15 The valve stem 65 has a shoulder 66 which bears against the bottom face of the cross member 62 and is provided with a valve head 67 threaded thereon at its lower end and locked in place by a lock nut 67'. The valve head 67 is 20 adapted to engage a valve seat 69 formed in the outer member 51 below the ports 60 in the inner member. In this form of my invention the valve seat 69 is shown as being formed on the lower end of an intermediate section 13a in the member 25 13 which is threaded in a bottom section 13b as indicated at 70. The upper end of the reduced portion 64 of the valve stem is shown as being threaded and is provided with a nut member 72, such nut being associated with a lock nut 73 held 30 in place by a key 74 to hold the nut against rotation on the pin 64. A compression spring 75 is interposed between the bottom face of the nut member and the upper face of the cross member 62.

35 When the bailer of the type shown in this form of my invention is assembled, the reduced portion 52 is inserted through the bushing 53 and the packing gland 54 in the member 55. The valve member 58 is then installed and locked in place by means of the cage member 59. When this has 40 been accomplished, the valve member 58 is drawn up into tight engagement with the seat 57 and may be locked there by means of a suitable clamp or collet on the outer end of the section 52. The valve stem 65 is inserted in the cage with the nuts 72 and 73 adjusted to place the spring 75 under the desired compression. The member 13a is then screwed in place on the member 55. When 45 this has been done a spreading feeler (not shown) is inserted through the opening 77 which normally contains a screw plug 78, and this feeler is adjusted between the nut 72 and the bridge 62 so as to bring the shoulder 66 into tight engagement with the bridge 62. The valve 67 is 50 then screwed onto the lower end of the stem 65 until it comes into tight pressure engagement with the seat 69. The feeler is then removed, the plug 78 is inserted and the valve assembly is 55 ready for use. It will be observed that when a bailer with parts connected and adjusted as described above, is freely suspended the sealing faces 57 and 58 are in pressure engagement and the valve 67 is also in pressure engagement with its seat so that the air chamber which incorporates the member 52 and that portion of the outer member 51 which is above the seat 69, is positively sealed and isolated from the sand chamber.

When the unit arranged in this manner is lowered into the bottom of a well until the outer member 51 engages the bottom, the downward movement of the upper member continues until the shoulder 80 on the upper end of the section 52 engages the top of the bushing 53 at which time the parts occupy the relative positions 70 shown in Fig. 3. When this occurs it will be 75

observed that the valve between the air chamber and the sand chamber has been opened and the great differential pressure which exists between the air chamber and the pressure fluid in the bottom of the well fills the bailer with pressure fluid drawing sand and debris into the sand chamber and compresses the air in the upper end of the air chamber.

When the bailer is lifted from the well after it has been filled with pressure fluid in this manner, the check valve in the bottom of the sand chamber or outer member supports the charge in the sand chamber and maintains it substantially under the pressure it had when forced in by the well pressure. The first action 15 upon upward movement is to expand the two telescoping members and thereby close the valves 67-69 and 58-57.

When the unit has reached the surface of the ground the discharge valve corresponding to 20 valve 44-45 is opened, establishing communication between the sand chamber and the atmosphere thereby creating a condition within the bailer in which the pressure in the sand chamber is greatly reduced as compared with the 25 pressure in the air chamber. When this condition has been created, the pressure fluid in the air chamber depresses the valve 69 against the action of the spring 75 to the broken line 30 position "B" shown in Fig. 2 thereby permitting the pressure fluid in the air chamber to discharge or unload the bailer. This relative movement of the valve 69 with respect to its seat, is entirely automatic and is permitted even when the bailer is in a horizontal position or when the 35 bailer is freely suspended with the parts in fully extended position since the weight of the outer member is carried on the inner member through the medium of the valve or nut 58 and its co-operating shoulder 57.

40 The opening action of the valve when the two members are collapsed is effected through the medium of the shoulder 66 which is engaged by the lower end of the inner member, and in order that the valve may be immediately opened 45 with a "snap" action, as soon as the bailer engages the bottom of the hole (that is, without any delayed movement when the units are collapsed) it is preferable that the distance between the face of the valve 67 and the shoulder 66 be such that the shoulder 66 engages the underface of the cross member 62 when the valve 67 is in pressure engagement with its seat and the valve or nut 58 is in pressure engagement with its corresponding seat 57. In the form of 50 my invention described herein, this is accomplished by threading the valve on the stem and using a spreading tool between the nut 72 and the bridge 62 in the manner described above.

55 The air chamber of the bailer may be provided with a relief valve for controlling the pressure in the air chamber at any predetermined maximum value as the bailer is withdrawn from the well. This valve may be of any conventional type, one form of such valve being indicated by 60 reference numeral 81.

65 It is to be understood that while I have herein described and illustrated certain preferred forms of my invention that the invention is not limited to the precise details of construction described 70 herein, but includes within its scope whatever changes fairly come within the spirit of the appended claims.

I claim as my invention:

1. In a bailer, the combination of: an upper 75

- valve being adapted to engage said seat when said members are extended; cooperating shoulder means on said members above said cage adapted to interengage when said members are suspended 5 for supporting the lower member in the upper member; and a shoulder on said valve stem adapted to be engaged by the underside of said bridge, whereby said valve is depressed away from its seat when said members are collapsed.
- 10 10. In a bailer the combination of: an upper tube member and a lower tube member telescopically connected; a cage on the bottom of said upper member within the upper end of said lower member; a bridge piece across the bottom of said 15 cage; a valve stem extending upwardly through said bridge; a nut threaded on the upper end of said stem; a compression spring interposed between said nut and said bridge; a valve seat in said lower member below said cage; a valve on the lower end of said valve stem below said seat, said 20 valve being adapted to engage said seat when said members are extended; cooperating shoulder means on said members above said cage adapted to interengage when said members are suspended 25 for supporting the lower member in the upper member; and a shoulder on said valve stem normally engaging the underside of said bridge when said members are extended whereby said valve is forced away from its seat immediately when said 30 members are collapsed.
11. In a bailer, the combination of: an upper tube member and a lower tube member telescopically connected, said upper member having a ported bottom portion extending into the top of said lower member; a valve seat in the top portion of the lower member below the bottom of said upper member; a valve below said seat adapted for engagement therewith to form an air 35

chamber and a sand chamber in said upper member and said lower member respectively when said members are extended; a valve stem on said valve having its upper end secured in the bottom of said upper member for yieldable downward movement relative to said upper member; cooperating shoulder means on said members above the lower end of said upper member adapted to interengage when said members are suspended for supporting the lower member in the upper member; 10 and a shoulder on said valve stem adapted to be engaged by the bottom of said upper member when said members are collapsed for depressing said valve away from its seat.

12. In a bailer, the combination of: an upper tube member and a lower tube member telescopically connected, said upper member having a ported bottom portion extending into the top of said lower member; a valve seat in the top portion of the lower member below the bottom of said 20 upper member; a valve below said seat adapted for engagement therewith to form an air chamber and a sand chamber in said upper member and said lower member respectively when said members are extended; a valve stem on said valve 25 having its upper end secured in the bottom of said upper member for yieldable downward movement relative to said upper member; cooperating shoulder means on said members above the lower end of said upper member adapted to interengage when said members are suspended for supporting the lower member in the upper member; and a shoulder on said valve stem normally engaged by the underside of said bridge when said members are extended and adapted to force said valve away 30 from its seat immediately when said members are collapsed.

WILLIAM J. FLURY.
